PAINT ROLLER

Roy Baggett, Jr., 18610 Matthews, Riverview, Mich.
Filed Apr. 23, 1962, Ser. No. 189,422
5 Claims. (Cl. 29—110)

This invention relates generally to paint rollers and refers more particularly to paint rollers designed to paint the inside corners of a room.

One of the essential objects of the invention is to provide a paint roller wherein the peripheral surface of the rotatable member is formed of frusto-conical sections defining an angle therebetween less than 90°, one section being inclined with respect to the axis of rotation more than the other.

Another object of the invention is to provide a paint roller wherein the large ends of the sections of the peripheral surface are of the same diameter and joined to one another intermediate the ends of the member, and the small ends of the sections are disposed adjacent the ends of the member.

Another object is to provide a paint roller wherein the large ends of the frusto-conical sections are joined in a plane normal to the axis of rotation, one section forming an angle of approximately 45° with the normal plane.

Another object is to provide a paint roller wherein the other section forms an angle of approximately 30° with the normal plane.

Another object is to provide a paint roller wherein the rotatable member has a core composed of a cylindrical sleeve and frusto-conical sections.

Another object is to provide a paint roller wherein sleeve and core sections are formed of cardboard sheet material, and the core sections are supported interiorly by a transversely split resilient ring member.

Other objects and features of the invention will become apparent as the description proceeds, especially when taken in conjunction with the accompanying drawings, wherein:

FIGURE 1 is an elevational view of a paint roller embodying my invention, shown in use in an inside corner of a room.

FIGURE 2 is an end elevation of the rotatable member forming part of the paint roller.

FIGURE 3 is a sectional view taken on the line 3—3 of FIGURE 2.

FIGURE 4 is a sectional view taken on the line 4—4 of FIGURE 3.

FIGURE 5 is an enlarged fragmentary view of a portion of FIGURE 1.

Referring particularly to FIGURE 1, the paint roller is generally designated 10 and comprises a rotatable member or head 12 and a handle 14. The handle 14 has a main shank portion 16 and an end journal portion 18 at right angles thereto. Disc 20 are rotatably mounted in axially spaced relation on the end portion 18 of the handle, and the rotatable member 12 is secured to the disc peripheries to be rotatable therewith with respect to the handle. Preferably this is merely a friction connection between the rotatable member and the discs so that the rotatable member may be replaced when and if desired.

The invention concerns the rotatable member or head 12 which is shown removed from the handle in FIGURES 2, 3 and 4. The rotatable member comprises a core which includes the cylindrical sleeve 22 and the frusto-conical sections 24 and 26 which are concentric with and surround the sleeve. The sleeve 22 is preferably formed of cardboard or like sheet material which is inexpensive and of a flexible and yieldable nature. The sleeve 22 may be rolled from a flat sheet to the tubular shape shown, in which the longitudinal edges abut at 28 so that the sleeve

2

is of the uniform circular cross-section from end to end as shown.

The frusto-conical core sections 24 and 26 are likewise formed of cardboard or like inexpensive flexible and yieldable sheet material. The section 24 may be rolled from a flat sheet of material into the form of a frustum of a cone, as shown, the edges thereof meeting in abutting relation as indicated at 30. The small end 32 of the core section 24 snugly encircles one end of the sleeve 22 and is permanently secured thereto by any suitable means, such as glue.

The other section 26 may likewise be formed from a flat sheet of material into a frustum of a cone, as shown, with the edges thereof abutting along the line similar to that indicated at 30 in connection with section 24. The small end 34 of the section 26 is of the same diameter as the small end of the section 24, and snugly encircles the opposite end of sleeve 22, being secured thereto by any suitable means, such as glue.

The large ends of the sections 24 and 26 are of the same diameter and meet in abutting relation as shown at 36, being secured together at the junction by any suitable means, such as glue. Preferably the abutting end faces of the sections are cut so as to lie in a plane normal to the axis of rotation of the rotatable member, which coincides with the longitudinal axis of sleeve 22. A strip of tape 38 may be applied over the outer surface of the core sections 24 and 26 adjacent the juncture of the large ends thereof around the entire periphery of the core sections to close the crack at the junction between the sections.

As shown particularly in FIGURE 3, the junction of the large ends of the core sections lies in a plane normal to the axis of rotation of the rotatable member nearer the right end of the sleeve 22 than to the opposite end thereof. In axial section, seen in FIGURE 3, the peripheral surface of the core sections 24 and 26 are straight, and the length of the peripheral surface of core section 26 is greater than that of core section 24. The core sections define an angle of somewhat less than 90°, and preferably the core section 26 forms an angle with the normal plane through the juncture of the sections at the large ends thereof of 45°, while the section 24 forms an angle therewith of 30°.

The core sections are interiorly supported by a substantially annular transversely split ring 40. The ring 40 is preferably in the form of a wire of a flexible resilient material such as spring steel. The wire 40 in its free state will assume a larger circular form than that shown in FIGURE 4, since it is under compression within the core sections and thus held to a smaller diameter. The wire 40 thus bears against the large ends of the core sections at their juncture with one another, imposing a radially outward pressure thereon. Accordingly the core is strong enough to support itself against deformation when used to paint the corners of an interior space.

The core sections 24 and 26 are covered on their outer surfaces with a soft fibrous material 42, which may be lamb's wool for example.

In use, the roller is dipped into the paint to cover the lamb's wool, and then the roller may be applied to a wall 46 near the corner 48 formed by that wall with another wall 50. These corners are almost always 90° as shown, and by reason of the less than 90° angle between the core sections 24 and 26, only one wall, in this instance 46, need be painted in the corner at a time. In other words, if one wall is to be painted one color and the other another color, such as often is the case in the corner between a wall and ceiling, this roller is well suited to the performance of the function. The core sections 24 and 26 are yieldable to conform to irregularities in the wall surface. When the lamb's wool covering core section 26 paints wall 46 in the corner, the lamb's wool on the other core section 24 is

ree of contact with the wall 50, because of the relief angle.

Since the rotatable member is frictionally supported on the discs 20 by engagement of the peripheries of the discs with the inner surface of sleeve 22, it may be readily removed and reversed to present the shorter core section 24 in the outer end of the handle. Then a narrower strip of corner paint can be applied by the lamb's wool on the core section 24, where a narrower strip is desired, the opposite side of the roller periphery providing relief so that the other wall will not be painted.

The lamb's wool is preferably a resilient sleeve which is not permanently secured to the core. Hence it may be stretched and slipped off the core and reversed when one side becomes worn.

What I claim as my invention is:

1. A rotatable paint roller head, the peripheral surface of which comprises first and second frusto-conical sections each of which is uninterrupted and continuous, the large ends of said sections being of the same diameter and joined to one another intermediate the ends of said head, said sections tapering toward opposite ends of said rotatable head from the joined large ends thereof, the angle between the conical sections being less than 90°, and said first section being inclined with respect to the axis of rotation of said head more than said second section, the small end of said first section being disposed at one end of said head and the small end of said second section being of the same diameter as that of the first section and disposed at the opposite end of said head, the large ends of said sections being joined in a plane normal to the axis of rotation of said head located nearer the said one end of said head than the opposite end thereof.

2. The structure defined in claim 1, wherein said second section forms an angle with respect to said normal plane of approximately 45° and said first section forms an angle with said normal plane of approximately 30°.

3. A rotatable paint roller head comprising a core, said core including a cylindrical sleeve and first and second

frusto-conical core sections encircling said sleeve in concentric relation therewith, said sleeve and said sections being separately formed elements permanently secured together, said sections each being formed of a light gauge sheet material shaped as an annulus to provide the frusto-conical form aforesaid, the small end of the first section being joined to one end of said sleeve and the small end of the second section being of the same diameter as that of the first section and joined to the opposite end of said sleeve, the large ends of said sections being of the same diameter and joined to one another intermediate the ends of said sleeve, said sections defining a substantial angle therebetween, a substantially annular, transversely split resilient element compressed within the space between said core sections and sleeve in concentric relation therewith and in bearing engagement with said sections at the junction between the large ends thereof to impose a radially outward pressure thereon.

4. The structure defined in claim 3, wherein said sleeve and core sections are separately formed cardboard elements permanently secured together at the points where they join one another.

5. The structure defined in claim 4, wherein the junction between the large ends of said core sections is disposed in a plane normal to the axis of rotation of said rotatable member nearer to the said one end of said sleeve than to the other, said first section forms an angle of approximately 30° with said normal plane and said second section forms an angle of approximately 45° with said normal plane.
